UNITED STATES PATENT OFFICE.

A. P. WINSLOW, OF CLEVELAND, OHIO:

ROOF FOR RAILROAD-CARS.

Specification of Letters Patent No. 25,071, dated August 9, 1859.

To all whom it may concern:

Be it known that I, A. P. WINSLOW, of Cleveland, in the county of Cuyahoga and State of Ohio, have invented certain new and useful Improvements in Roofs for Railroad-Cars and Hurricane-Decks of Vessels; and I do hereby declare that the following is a full and exact description of the same, reference being had to the annexed drawings, making part of this specification, in which—

Figure 1, is a plan view. Fig. 2, a longitudinal section in the direction of the line α , α , in Fig. 1. Fig. 3, is a transverse section in the direction of the line α' , α' , in Fig. 1. Figs. 4, and 5, are detached sections which will be referred to in the following description.

Like letters denote like parts in the several views.

The outside covering A, Figs. 1, 2, 3, of the roof may be of wood covered over in the usual manner. In Fig. 1, a portion of this outside roof is removed for the purpose 25. of showing my improvement.

The rafters B, may be made and connected to the rail road car, and the upper cabin of vessels, in any desirable manner suitable for this purpose. In the sides of each rafter 30 is cut a groove C, Fig. 4, the curve of which conforms to the top of the rafter, and extends the entire length of it as seen in Fig. 5. Between the rafters in the grooves is placed a metallic plate, or sheet, D, which 35 extends the entire length across the car as indicated in Figs. 1, 3, 5. The ends of the plates D, extend over the sides of the car, or cabin to the inside of the molding or cornice E, of the roof. This cornice prevents the 40 plates D, from sliding laterally out of place. On the top of each rafter is fastened the cap F, which extends the whole length of the rafter as seen in Fig. 3. The sides of 45 this cap are so turned that the sides lap down on the plates D, as seen in Fig. 2. The plates herein shown are curved for the purpose of conveying all moisture, or rust, that may get under the roof A, to the center of the plates, from the sides and grooves. 50 Straight, angular, or corrugated plates may be employed instead of the plates D, but I

prefer the latter, as I consider it better adapted to the purpose designed.

Between the roof or sheeting A, and the plates D, is formed a chamber G, into which a current of air is continually passing 55 through the openings H, at each end of the plates, and through these openings is discharged all wet, dust, &c., which may gather in the chambers. The chambers being open 60 to the atmosphere by means of the openings H, the interior of the car is rendered much more cool, and comfortable, than when the heated air is confined as is now the case.

The plates are made to fit not tightly in 65 the grooves, but so that they will move readily, and adjust themselves to the straining and springing of the car, or vessel, and so that in case one of the plates should become injured that it may be easily withdrawn, and replaced. In the ordinary mode 70 of covering the roofs of cars with tin, or iron, the strain, and continual jarring of the cars, and the expansion, and contraction, cracks and loosens the metallic sheets from 75 the roof. Then leakage follows, which does more or less damage particularly on freight cars; as the goods become injured to a greater or less extent, when thus exposed, and when the roof is composed entirely of 80 wood, the joints or seams become opened by exposure to the weather, and rocking of the cars, which again exposes the freight to injury, again the wood roof is at all times liable to be fired by sparks from the engine. With my improved roof, these difficulties are obviated as all leakage from the 85 roof A, is conveyed by the plates D, through the openings H, and in case the roof A, should be fired, the metallic roof below 90 would prevent the fire from injuring the freight, so that the train could be stopped, and the fire subdued without injury to the roof, or the goods.

This manner of constructing the roof of 95 rail road cars is much less expensive, and more durable than the ordinary metallic roofing, and it may be applied to the hurricane decks of steam boats, propellers and other vessels using cabins with hurricane 100 decks. All structures of this kind are more or less subject to continual strain and rack-

ing of the timbers, and this roof by its peculiar construction is rendered flexible to a certain extent, and will adjust itself to the working of the car or vessel.

- 5 What I claim as my improvement and desire to secure by Letters Patent is,
The plates D, caps F, and grooved rafters

B, when arranged substantially as herein set forth for the purpose described.

A. P. WINSLOW.
